United States Patent Office

Des. 194,952
Patented Apr. 2, 1963

194,952

GRILLWORK OR SIMILAR ARTICLE

Philip C. Patterson, Pasadena, and Whitney R. Smith, South Pasadena, Calif., assignors to Thorpe Insulation Company, doing business as Thorpe Products Company, Los Angeles, Calif., a corporation of California

Filed Mar. 27, 1961, Ser. No. 64,508

Term of patent 14 years

(Cl. D54—2)

Fig. 2.

Fig. 1.

FIG. 1 is a side elevational view of a grillwork showing our new design; and

FIG. 2 is an end view taken from the right side of FIG. 1.

The design of FIG. 1 is repeated both vertically and horizontally as indicated.

We claim:

The ornamental design for a grillwork or similar article, substantially as shown and described.
